TAPE TIME RECORDER WITH
DIFFERENTIATED RECORDSHarold E. Hobby, Gardner, Mass., assignor to
Simplex Time Recorder Co., Gardner, Mass.,
a corporation of Massachusetts

Application October 13, 1945, Serial No. 622,153

3 Claims. (Cl. 101—93)

1

This invention relates to a machine to be used in the making of time records on a paper tape or other continuous record surface, and in differentiating between two classes of records, such as start and stop, or in and out.

It is the general object of my invention to provide improved mechanism for producing and recording differentiated records. To the accomplishment of this purpose, I provide an auxiliary printing device bearing two different symbols, together with means for moving either symbol into operative position.

I also provide improved actuating means by which the symbols are shifted in definite relation to the printing of the time record.

A further object of the invention is to provide an improved switch mechanism by which a circuit may be closed for a definite brief interval whenever a control circuit is either opened or closed.

My invention further relates to arrangements and combinations of parts which will be herein-after described and more particularly pointed out in the appended claims.

A preferred form of the invention is shown in the drawings, in which

Fig. 1 is a front elevation of a time recorder embodying my invention;

Fig. 2 is a plan view thereof, with parts of the casing omitted;

Fig. 3 is a side elevation, with certain parts shown in section; and

Fig. 4 is a circuit diagram.

Referring to the drawings, the time recorder in which my invention is shown comprises a casing C in which type wheels W are rotatably mounted on a shaft 10 which is intermittently advanced by a motor M, operating through a lever 11, feed pawl 12 and ratchet wheel 14 (Fig. 1). The usual holding pawl 15 prevents backward rotation. The type wheels may register any desired data and are shown in Fig. 3 as recording the month, day, hour and minute. The minute wheel is usually fixed on the shaft 10 and any suitable reduction gearing is provided to secure the desired relative rotation for the slower wheels.

A shelf or table 16 is mounted in fixed position on the frame F of the recorder, and a tape T is drawn upward through a notch or slot in the table 16 from a supply roll 17 and is delivered at the left side of the machine. The tape T passes under the type wheels W and also under an ink ribbon 20 mounted on spools 21.

A hammer 24 is mounted on an arm 25 which

2

is fixed on a shaft 26 (Fig. 2) rotatably supported in the sides of the frame F. A second arm 27 is fixed to the shaft 26 and extends over the upper end of a plunger 28, vertically slidable in a hammer-actuating solenoid 30. When the solenoid is energized, the plunger 28 operates through the arm 27, shaft 26 and arm 25 to swing the hammer 24 upward to print a record from the type wheels on the tape T.

After receiving the printed record, the tape T is drawn forward between a friction or feed roll 32 and a pressure roll 33. The roll 33 is mounted on a lever 34 pivoted at 35, and is yieldingly pressed against the tape T by a spring 36. It can be manually raised to free the tape.

The friction or feed roll 32 is mounted on a cross shaft 40 (Fig. 3) rotatable in fixed bearings and connected by beveled gears 41 and 42 (Fig. 2) to a ratchet wheel 43 loose on the hammer shaft 26 (Fig. 3). A feed pawl 44 is mounted on an arm 45 fixed to the shaft 26 and normally engages a fixed stop 46.

As the hammer 24 is swung upward to stamp a record (or clockwise in Fig. 3), the feed pawl 44 is drawn back one tooth, while the ratchet wheel 43 is held from backward rotation by a holding pawl 47. As the hammer is returned to its normal lower position by gravity, the feed pawl 44 advances the ratchet 43 one space and is locked against the stop 46 to prevent over-feeding. The tape T is thus advanced after the printing of each record and during the return or downward movement of the hammer.

The parts thus far described are all of usual commercial construction and are substantially as shown in the prior patent to Deane and Dell, No. 2,326,765.

As previously stated, my present invention relates more particularly to the provision of differentiated symbols to designate different classes of records. These symbols may indicate widely different items, and are shown herein as indicating whether current is "on" or "off" in an electric oven X (Figs. 1 and 4).

The symbols are formed on an auxiliary printing device shown as an arm 50 (Figs. 1 and 3) pivoted on a bushing 51 which also provides a bearing for the front end of the type wheel shaft 10. The arm 50 thus swings concentric with the type wheels, and is provided on the lower face with the symbols On and Off to indicate whether the load is "on" or "off."

The arm 50 is connected by a link 52 (Fig. 1) to an armature 53, pivoted at 54 and associated with a magnet 55. A spring 56 normally holds

the armature away from the magnet and thus holds the arm 50 in the "off" position shown in Fig. 1.

The operating circuit of the magnet 55 includes contact points 60 (Fig. 1) which are normally separated but which may be closed by depression of a lever 61, acting through a plunger 62. The lever 61 is provided with a roll 63 engaging a star-wheel 64 which is fixed on the shaft 40 and rotates with the friction wheel 32.

Assuming that the parts are in the position shown in Fig. 1, the next tape-feeding advance movement of the roll 32 will depress the roll 63 on the lever 61 and will hold it depressed by a high point on the star wheel 64 until a second advance or feeding movement of the star wheel takes place. As each movement of the star wheel is synchronized with a return movement of the hammer 24 after a printing blow, the auxiliary device 50 will be alternately shifted from right to left and from left to right as viewed in Fig. 1, after each successive record is printed and as the tape T is intermittently advanced.

A single-pole, double-break switch or relay 70 (Fig. 1) is provided in the hammer circuit in the casing C and comprises normally closed contacts 71 associated with the plunger 72 of a solenoid 73. When the solenoid is energized, the plunger 72 rises and engages an upper plate 74, separating the contacts 71 and breaking the hammer circuit to prevent a second impression blow after the downward rebound of the hammer, which second blow will occur if the circuit of the hammer solenoid 73 remains closed.

A switch 80 (Fig. 1) is connected to be closed momentarily each time the main load switch 81 is either opened or closed. The switch 80 comprises normally open contacts 82, with one of the contacts mounted on a movable plate 83 which is normally pressed outward by a spring 84. A light flexible cam member 85 on the plate 83 is positioned for engagement by a collar 86 on the upper end of a solenoid plunger 87, vertically slidible in a solenoid 88 and having a weight 89 at its lower end.

When the main switch 81 is closed the solenoid 88 will be energized and the plunger 87 will be moved upward to the dotted line position shown in Fig. 1. As it moves upward, the collar 86 will force the flexible contact member 85 to the left and will thus close the contacts 82 for a brief interval. The contacts will immediately reopen, and will remain open as long as the switch 81 is closed and the collar 86 remains in its raised position.

Assuming $\frac{3}{4}$ " travel for the plunger 87, the first $\frac{1}{16}$ " travel may close the contacts 82, the next $\frac{3}{8}$ " travel may hold them closed, and they may reopen during the last $\frac{1}{16}$ " travel. The circuit remains closed only a small fraction of a second.

When the switch 81 is opened, the plunger 87 and collar 86 will drop under the influence of gravity and the weight 89, thus again momentarily closing the contacts 82.

The operation of my invention will be more clearly understood by reference to the circuit diagram shown in Fig. 4. Line wires L and L' supply current for the oven X through the main switch 81, and also supply current through the same switch for the solenoid 88. Current is supplied through line wires L2 and L3 for the type wheels and impression mechanism in the recorder.

The type-wheel driving or time motor M is di-

rectly connected across the line wires L2 and L3. The magnet 55 which shifts the auxiliary printing device 50 is connected across the line wires L2 and L3 through the contacts 60, controlled by the star wheel 64. The hammer 24 is operated by the solenoid 30 which is connected through the relay contact points 71, and the hammer solenoid 30 and relay solenoid 73 are connected in parallel across the line wires L2 and L3 through the load-controlled contacts 82. The shifting of the auxiliary printing device 50 by the magnet 55 is in part dependent on the open or closed condition of the contacts 60, as effected by the star wheel 64 on each return movement of the hammer 24.

Whenever the main switch 81 is either opened or closed, the contacts 82 are momentarily closed, thus energizing the hammer coil 30 and the relay coil 73 and also the magnet 55 if the contacts 60 are closed. The hammer coil then acts to swing the hammer upward to strike a blow and thus print a record, and the relay coil 73, after a very brief interval, separates the contacts 71, thus releasing the hammer and preventing a second actuation thereof until the contacts 82 have been opened to break both the hammer and the relay circuits.

I have thus provided very simple electrical controls by which the opening or closing of the switch 81 will cause the recorder to make a record of the time of such opening or closing and to designate successive records as either "on" or "off."

It will be understood that the circuit-closing switch 81 may be included within the casing C, or may be associated with the oven X, or with any other device of which a record is to be kept. Furthermore, the circuit through the wires 100 and 101 (Fig. 4) may be closed by any other kind of a device which will close and thereafter open the circuit promptly, or the circuit may be closed manually. The line wires L2 and L3 may be the same as the wires L and L', if the same current is used.

Having thus described my invention and the advantages thereof, I do not wish to be limited to the details herein disclosed, otherwise than as set forth in the claims, but what I claim is:

1. In a time recorder having a record sheet, sheet feeding means, and periodically advanced printing devices, in combination, an auxiliary printing device bearing two different printing symbols, an impression hammer, a solenoid to move said hammer to make an impression from said regular and auxiliary printing devices, a circuit for said solenoid, and means to shift said auxiliary printing device to move one symbol into printing position and the other symbol out of printing position alternately and before each successive operation of said hammer.

2. In a time recorder having a record sheet, sheet feeding means, and periodically advanced printing devices, in combination, an auxiliary printing device bearing two different printing symbols, an impression hammer, a solenoid to move said hammer to make an impression from said regular and auxiliary printing devices, a circuit for said solenoid, magnetic means to shift said auxiliary printing device to move one symbol into printing position and the other symbol out of printing position, mechanism effective to render said magnetic means operative after every other operative movement of said impression hammer, and means to return said auxiliary printing device to its initial position when said magnet means is deenergized.

3. In a time recorder having a record sheet, sheet feeding means, and periodically advanced printing devices, in combination, an auxiliary printing device bearing two different printing symbols, an impression hammer, a solenoid to move said hammer to make an impression from said regular and auxiliary printing devices, a circuit for said solenoid, magnetic means to shift said auxiliary printing device to move one symbol into printing position and the other symbol out of printing position, additional means to return said symbols to initial position when said magnetic means is de-energized, and mechanism effective to render said magnetic means operative after every other operative movement of said impression hammer, and said latter mechanism including a switch associated with an external load circuit and means to close said switch momentarily each time said external load circuit is either opened or closed.

20 HAROLD E. HOBBY.
